UNITED STATES PATENT OFFICE.

HARRY A. MASSEY, OF EAST ST. LOUIS, ILLINOIS.

MOP.

1,117,209.

Specification of Letters Patent. Patented Nov. 17, 1914.

Application filed April 16, 1914. Serial No. 832,343.

To all whom it may concern:

Be it known that I, HARRY A. MASSEY, a citizen of the United States, residing at East St. Louis, in the county of St. Clair and State of Illinois, have invented a new and useful Mop, of which the following is a specification.

This invention relates to improvements in mops.

10 An object of the present invention is to provide a mop which may be advantageously used with uneven or irregular surfaces, the mop adjusting itself to any irregularities encountered for the efficient cleaning thereof.

15 A further object is to provide a mop in which the mopping fibers may be easily and readily detached from a supporting frame for replacement, either as a whole, or in part.

20 A further object is to provide a mop which will be simple in construction and subject to economic manufacture: strength and lightness being also obtained with the 25 present construction.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, can be made within the scope of what is claimed, without departing from the spirit of the invention.

35 In the drawings accompanying this specification and forming a part thereof, the preferred embodiment of my invention is illustrated, in which:—

40 Figure 1 is a view in perspective of the mop frame. Fig. 2 is a view in perspective of the mop, with the several parts in assembled relation and ready for use. Fig. 3 is a fragmental view, partially in section, 45 of the mopping fibers and adjacent parts. Fig. 4 is a sectional view showing the relation of the inner and outer binders, the mopping fibers, and binding wire.

45 Referring to the drawings in which similar reference numerals designate corresponding parts throughout the several views, 5 designates generally, a frame preferably formed of wire and including a continuous coil 6 which bulges at its lower portion in a spiral manner as at 7.

The one extremity of the wire leading

from the coil is bent to form the three arms 8 defining a triangular figure or frame with the upstanding loops 9 at the respective apices. The upstanding loops 9 curve inwardly as at 9' at their central portions for the reception and securement of the mop fibers as will be hereinafter more fully explained.

As illustrated in detail in Fig. 4 a pair of superimposed binders 13 and 14 are provided and between which are arranged the mopping fibers 14'. The mop fibers or mopping material is securely held in place with relation to the binders by the stitching 15, thus preventing its premature or accidental detachment. A binding wire 16 extends around the annular opening defined within the inner binder 14 and holds the binders and fibers to the frame as illustrated in Fig. 1. The ends of the wire 16 are twisted together as at 17 and project through the opening defined at the meeting ends 18 of the binders. The twisting of the ends 17 produces the requisite amount of tension within the binding wire and securely locks the fibers to the frame.

The binders with the intermediate fibers are mounted upon the triangular frame and with the binders proper lying adjacent the curved central portion 9' of the loops. The curvature in question is sufficient to prevent the binders from moving in either direction and thus prevents their accidental detachment. A handle 19 of wood or other suitable material is inserted within the coil 6 and may threadedly engage the same if it be so desired or may be forcibly moved into frictional engagement therewith. With the handle in place within the coil, the frame is adapted to move relatively to the handle so as to compensate for any irregularities which may be encountered during the use of the device. The terminal 20 of the coil is offset as illustrated in Fig. 1, thus imparting the requisite resiliency to the coil and allowing it to move relative to the triangular frame. The end arm of the triangular frame is curled about the offset end 20 as at 11 and projects centrally beneath the coil 6 and terminates in the loop 12. The latter is rigidly secured to one of the arms and held in position thereby. The lower or cross bar 10 being mounted directly beneath the coil, serves as a stop for the wooden handle 110 11 should it tend to move through, and beyond the coil. The spiral manner in which

the lower extremity of the coil is formed also allows the coil to flex and the mop frame to shift as described.

The fibers may be removed and replaced by loosening the binding wire 16 and removing the binders and the fibers from the frame. A new set of binders and fibers may then be placed upon the frame or the old ones may be repaired or renovated as circumstances may dictate.

Having thus fully described my invention, what I claim is:—

1. A device of the class described, comprising a frame, means adapted to resiliently secure the same to a handle, said frame provided with a plurality of upstanding loops.

2. A device of the class described, comprising a frame, a resilient coil carried thereby adapted to secure the same to a mopping handle, and a plurality of upstanding loops carried by said frame for the securingment of mopping fibers thereto.

3. A mop comprising a handle, a wire coil engaging the same and including a plurality of angularly disposed arms carried at the lower extremity thereof, said angularly disposed arms provided with upstanding loops for the securement of mopping material thereto, and a cross bar carried by said angularly disposed arms and extending beneath said coil.

4. A mop comprising a handle, a wire coil engaging the same and including an upper helical portion and a lower spiral portion, a plurality of angularly disposed arms carried by the lower spiral portion of said coil, said angularly disposed arms provided with upstanding loops for the securement of mopping material thereto.

5. A mop comprising a handle, a wire coil engaging the same and including an upper helical portion and a lower spiral portion, a plurality of angularly disposed arms carried by the lower spiral portion of said coil, said angularly disposed arms provided with upstanding loops for the securement of mopping material thereto, and a cross bar carried by said angularly disposed arms and extending centrally beneath said coil.

6. A mop comprising a handle, a spring coil carried thereby and provided with the lowermost convolution thereof bent to form a polygonal frame, said frame provided with upstanding loops at the apices thereof, the extremity of said frame extending centrally beneath said spring coil.

In testimony that I claim the foregoing as my own, I have hereto affixed my signature in the presence of two witnesses.

HARRY A. MASSEY.
